GUM MASSAGING AND TOOTH POLISHING
APPLIANCE

Leslie L. Fuller, Edmonton, Alberta, Canada

Application April 17, 1943, Serial No. 483,389

1 Claim. (Cl. 128—62.1)

This invention relates to improvements in gum massaging appliances, and constitutes improvements on my prior Patents Nos. 2,217,439 and 2,294,900, issued respectively, October 8, 1940, and September 8, 1942.

In my prior patents the gum massage appliance consisted of a plurality of aligned velum rubber cores or cups each encased in a covering or sheath of sponge rubber, which due to its absorbent properties is an excellent vehicle for carrying medicaments and in view of its velvet-like softness provides an ideal contact surface for gum massage appliances that is neither harsh, irritating or injurious to the most tender, inflamed or congested tissue, will not cause injury, damage to or recession of the gum tissue, the massage appliance utilizing the well known "cupping" action, through the establishment of suction by partial vacuum.

The principal object of the improvement constituting this invention is to provide a sponge rubber sheath enclosing only the rims of the velum rubber cups, instead of the whole surface of said cups, and to further provide within the concavity of said cups a sponge rubber core of such structural shape as to define an annular channel between the said core and the inside wall of said sponge rubber sheath.

A further object of this invention is to form both the rim of both the velum cup and the enclosing rim sheath with a concavity preferably coextensive with the longitudinal axis of the appliance, the sponge rubber sheath, enclosing the rim of the cup being brought to a point at its periphery and the sponge rubber core within the cup projecting up only to the level of the rim of the velum cup.

With the foregoing and other objects in view, the invention resides in the novel arrangement and combination of parts and in the details of construction hereinafter described and claimed, it being understood that changes in the precise embodiment of the invention herein disclosed may be made within the scope of what is claimed without departing from the spirit of the invention.

A practical embodiment of the invention is illustrated in the accompanying drawing, wherein—

Figure 1 is a side elevational view of one form of gum massaging appliance.

Figure 2 is a plan view thereof.

Figure 3 is a detail sectional of one of the massaging cups taken on line 3—3, Figure 2.

Figure 4 is a sectional view similar to that of

Figure 3 illustrating a modified form of the invention, taken on line 4—4, Figure 5.

Figure 5 is an end elevational of the massaging cup.

5 Referring to the drawing, 10 denotes the handle of a gum massaging appliance shaped somewhat in the form of a conventional tooth brush handle, on the forward end of which is mounted a row of gum massaging elements 11, and which are fixed to said handle as by the rubber sheath 12, or in any other suitable manner. In the form shown in Figure 1, four such massaging elements 11 are shown preferably spaced equal distances apart. As each of the massaging elements 11 are identical in form and structure a description of one will suffice.

The massaging element 11, see Figure 3, comprises a velum rubber cup 13 of truncated conical form provided with a cup shaped concavity or recess 14 forming a tapered rim portion 15. The cup 13 should be of such a length as to provide a requisite amount of flexibility thereof in all lateral or radial directions. Encasing the rim portion 15 on each side thereof is a sponge rubber sheath 16 that extends a substantial distance above the peripheral edge of said rim portion to define a flat edge portion 17. The outer wall surface 18 of the sheath 16 is of inverted truncated conical form, as clearly shown in Figure 1, the upper peripheral edge being preferably beveled as at 19. The sponge rubber sheath 16 is vulcanized to or secured by cementation to the rim portion 15 of the velum cup 13.

Disposed centrally within the concavity 14 of the velum rubber cup 13 is a sponge rubber core 20 that is preferably of truncated conical form, said core being seated directly on the bottom of said concavity and secured thereto in the same manner as the sheath 16 is secured to said cup 13. The height of the core 20 is such that its upper end lies in the plane of the flat edge portion 17 of the sponge rubber sheath 16. Between the core 20 and the inside wall of the sheath 16 is an annular channel 21 that forms a well or pocket for the reception of a medicament as will be hereinafter described.

The advantages of the above described construction in massaging device is: first, that by enclosing the rim only of the velum cup, instead of the whole external surface as in my prior Patent No. 2,298,900, the massaging appliance is more easily cleaned after use and the advantages of having the surfaces that come in contact with the gum and teeth encased in sponge rubber are retained; secondly, the sponge rubber core 20,

as herein constituted, is more flexible and makes better contact with the gum tissue; and third, the channel 21 between the core 20 and sheath 16 allows of greater flexibility of the cup 13 and constitutes a well to hold medicaments.

In the form of massaging appliance shown in Figures 4 and 5, only one massaging element 11a is shown. It is to be understood that a row of such elements 11a are secured as by the sheath 12a, or in any other manner to the handle 10a in the same manner as that described above in the form shown in Figures 1 to 3. The massaging element 11a comprises a velum rubber cup 13a having a concavity 14a of the same general form as the velum cup 13. Secured to the rim portion 15a is a sponge rubber sheath 16a and within the concavity 14a is seated a sponge rubber core 20a, the upper end 25 of which lies in the plane of the peripheral edge of the velum cup 13a as clearly shown in Figure 4. Both the sponge rubber sheath 16a and the sponge rubber core 20a are secured to the velum rubber cup as by vulcanization or cementation. The upper end of the sponge rubber sheath is provided with a tapered edge portion 26 which extends above the plane of the core end 25. Formed between the core 20a and the inside wall of the sheath 16a is an annular channel 21a forming a pocket or well for a medicament.

Formed centrally in the rim 15a of the velum rubber cup coextensive with the longitudinal axis of the handle 10a are opposed concavities 26, and the sponge rubber sheath 16a encasing the rim portion 15a are likewise formed with opposed concavities 27 superimposed over the rim concavities 26. The concavity formations 26 and 27 providing a "cupping down" of the rim of the velum cup and the enclosing sponge rubber sheath permits of a more perfect confirmation of the sheathed cup to the contour of the teeth, and gum margins and to deeper penetration into the interdental spaces, the cup rims mushrooming out until the surface of the sponge rubber core

comes into contact with the gum tissue. The massaging appliance of Figures 4 and 5 possesses the same advantages as enumerated above with reference to the massaging appliance of Figures 1, 2 and 3.

The gum massaging appliance as above described is efficient in both gum massage and tooth cleaning and will not cause irritation, injury or gum recession.

It will be further noted that the same principle of construction; i. e., a series of velum cups attached to a base, each cup being incased (except as to its base) in sponge rubber and having a sponge rubber core within its concavity and attached to the base of said concavity and having a channel between the sides of the core and the inner wall of the cup, may be applied to a general body massaging appliance in the form of a glove, mitten, pad or other suitable unit.

Having thus set forth and disclosed the nature of this invention, what is claimed is:

A massaging appliance comprising a handle, a plurality of similar massaging elements arranged in a row in spaced relation on an end portion of said handle, each massaging element comprising a rubber body fixed on said handle, said rubber body having a central cavity at its free upper end providing a rim portion, said rim portion having opposed concave cut-out portions, the cut-out portions of all of said massaging elements being aligned co-extensively with the longitudinal extent of said handle, a sponge rubber sheath encasing both sides of said rim portion and secured thereto, said sheath extending beyond the peripheral edge of said rim portion and having concave portions corresponding to and aligned with said cut-out portions, a sponge rubber core seated in said cavity and secured to said rubber body, the upper free end of said core being substantially in the plane of the peripheral edge of said rim portion, said core and sheath having an annular channel therebetween.
